[57] **CLAIM**

The ornamental design for pocket watch case, as shown and described.

DESCRIPTION

FIG. 1 is a front elevational view of a pocket watch case showing my new design, the rear being a mirror image thereto;

FIG. 2 is a right side elevational view thereof;

FIG. 3 is a right-front perspective view thereof;

FIG. 4 is a top plan view thereof; and,

FIG. 5 is a left front perspective view thereof.

The broken line showings of watch stems and hinges in FIGS. 1-4 are environmental only and form no part of the claimed design.
